UNITED STATES PATENT OFFICE.

CHARLES EISLER, OF BLOOMFIELD, NEW JERSEY, ASSIGNOR TO WESTINGHOUSE LAMP COMPANY, A CORPORATION OF PENNSYLVANIA.

FILAMENT-WINDING MACHINE.

1,338,498.

Specification of Letters Patent. Patented Apr. 27, 1920.

Application filed December 29, 1914. Serial No. 879,483.

To all whom it may concern:

Be it known that I, CHARLES EISLER, a citizen of the United States, and a resident of Bloomfield, in the county of Essex and State of New Jersey, have invented a new and useful Improvement in Filament-Winding Machines, of which the following is a specification.

My invention relates to wire-working machines, and it has special reference to machines for making helical metallic filaments for incandescent electric lamps.

The object of my invention is to provide an automatically-operated machine of the character indicated above which shall be simple in construction and efficient in operation, and which shall be adapted to form helical filaments of widely varying dimensions and characteristics.

More particularly, my invention has for its object to provide a machine for automatically and continuously winding helical filaments of the type which is composed of a series of sections of closely-wound turns of wire separated by one or more turns of greater pitch than the turns composing the closely wound sections, and which is provided, at its ends, with loosely wound sections for attaching the filament to the leading-in wires of an incandescent lamp.

Of the accompanying drawings, Figure 1 is a perspective view showing a machine constructed in accordance with my invention; Fig. 2 is a front elevational view of the machine shown in Fig. 1; Fig. 3 is a side elevational view of the same machine as seen from the left of Fig. 2; Fig. 4 is a front elevational view of a modified form of winding disk; Fig. 5 is a side elevational view of the upper portion of the machine as seen from the right of Fig. 1; Fig. 6 is a vertical sectional view of the ratchet mechanism best shown in elevation in Fig. 5, the section being taken substantially along the line VI-VI of Fig. 5; Fig. 7 is a front elevational view of one form of cam disk adapted for use in my machine; Fig. 8 is an elevational view of a filament produced by my machine, and Fig. 9 is an enlarged elevational view of a filament section of a modified form.

In certain types of incandescent electric lamps, it is desirable to provide the filament in the form of a helix of wire, and it is customary to divide this helix into two or

more sections separated by a short interval of straight or loosely-wound wire, the filament being attached, at some or all of these intervals, to its supports. Such sectional filaments have heretofore been made by 60 winding a wire that is to compose one or more filaments around a mandrel wire of copper or steel in a continuous coil, dissolving the mandrel wire by means of a suitable acid, and thereafter forming the 65 loosely-wound spacing sections or "breaks" at proper intervals by manually opening up the coil by the insertion of a hot wire or blade. Obviously, this method of forming the spacing sections produces filaments that 70 are only approximately correct in the lengths of their sections and in the extent to which the coil is untwisted at the spacing intervals. A further disadvantage of the process heretofore in use is that the total length 75 of twisted filaments that can be formed in a single operation is limited by the length of the mandrel wire which can be used with hitherto-existing machines. In practice, this limiting length has been found to be 80 about two feet.

According to my present invention, I provide a machine for automatically accomplishing all of the results described above and having the additional advantages that 85 the several kinds of turns which make up a single filament are formed with much greater accuracy than has heretofore been possible, and that continuous supplies of mandrel wire and filament wire are used, 90 so that many yards of filament can be accurately wound without stopping the machine or giving it any attention. Furthermore, I provide the machine with various adjustments, whereby the characteristics of 95 the wound filaments may be varied at will with respect to the pitch of the filament helix, its diameter, the total number of turns in each filament, the number of turns in each section of the filament and the number of sections that compose each filament.

In general, my winding machine consists of a support carrying a spool of mandrel wire, a drum for drawing the mandrel wire from the spool and for receiving the mandrel wire after the filament wire has been wound upon it, and a rotating device interposed between the spool and the drum for causing a supply of filament wire to rotate rapidly around the mandrel wire while the 100 105 110

mandrel wire is being drawn without rotation from the spool to the drum and for thereby coiling the filament wire upon it. The winding drum is positively rotated in 5 order to draw the mandrel wire past the rotating winding device, and the speed of rotation of the drum is periodically increased for a moment by means of a cam device, in order to form one or two loosely- 10 wound turns that constitute a "break" between two adjacent sections. At greater intervals, corresponding to the total length of each filament, the speed of the drum is automatically increased for a longer period, in 15 order that a coarsely-wound terminal section may be formed in the coil. A further feature of my machine is a novel device for electrically heating the filament wire while it is being wound upon the mandrel wire, 20 such heating being necessary in order to soften the filament and to thereby prevent it from breaking during the winding operation.

For a better understanding of my invention reference may now be had to Fig. 2 25 of the accompanying drawing, which shows a device in which a supply of mandrel wire 1 is drawn horizontally from a spool 2, passes through a tensioning device 3, then 30 lengthwise through a guiding quill tube 4, then axially through a central opening 5 in a rotating winding plate or disk 6, and finally is wound upon a power-driven drum 7. The opening 5 may be provided by a 35 drilled jewel centrally held in the plate 6. A supply of filament wire 8 is carried by a metallic spool 9, which is secured to the rotating plate 6 near its periphery, and the filament wire is guided to the mandrel wire 40 1 by means of a flier device 10. Power for driving the various elements of the machine is derived from a motor 11, or other suitable prime mover, through a belt 12 and a pulley wheel 13 which is secured to one end 45 of a main power shaft 14 that is supported in bearings 15, 16, 17 and 18 secured to outwardly-extending arms 19, 20, 21 and 22 of a supporting frame 23. The frame 23 is mounted upon a bed plate 24, which may 50 be supported upon a table 25 or other convenient supporting means. As shown, the belt 12 passes around a pulley 26 secured to a countershaft 27 that is supported in brackets under the table 25. Sets of cone pulleys 28 are secured to the countershaft 27 55 and to the armature shaft of the motor 11, and are connected by means of a belt 29.

Proceeding to a more detailed description 60 of the machine, the spool 2, which carries the supply of mandrel wire, is supported on the table 25 by means of a standard 30 and a vertically adjustable support 31, which extends through a bearing 32 in the standard 30 and is maintained in its adjusted position by means of a set screw 33.

The tensioning device 3, through which the wire 1 passes after leaving the spool 2, consists of a guiding eyelet 35 and two oppositely-disposed toothed pressure members 36 and 37, the lower member 36 being stationary and the upper member 37 being vertically movable toward and from the member 36 and being pressed toward the member 36 by means of a compression spring 38 surrounding a rod 39 which supports the 75 pressure member 37. The rod 39 passes loosely through a supporting bracket 40 and is provided, at its outer end, with screw threads upon which are mounted a nut 41 and a milled lock nut 42. By manipulating 80 the nuts 41 and 42, the pressure which the toothed member 37 exerts upon the wire 1 may be readily adjusted. If desired, small strips of filer or other friction material may be interposed between the members 36 and 85 37 to increase the friction between these members and the wire 1.

The bracket 40 is supported upon one end of the quill tube 4, which is itself supported by a rod 43 that is vertically adjustable in 90 a bearing 44 secured to one end of a horizontal rod 45 which is adjustably held, by means of a set screw 46, in a bearing 47 rigidly attached to the upper end of the arm 22 of the frame 23. 95

After leaving the guiding quill tube 4, the mandrel wire is drawn centrally through the rotating winding disk 6, by means of which the filament wire is wound upon it. The disk 6 is secured to a spur gear wheel 100 50 by means of screws 51, a disk 52 of fiber or other electrical insulating material being interposed between the disk 6 and the gear wheel 50 for the purpose of electrically insulating the plate 6 from the remainder of 105 the machine. Some of the screws 51 extend from the disk 6 into the insulating disk 52, while other screws 51 extend from the gear wheel 50 into the disk 52, the screws in the two sets being displaced from one another 110 to prevent electrical connection between the disk 6 and the gear wheel 50. The gear wheel 50 is mounted on a short shaft 56 that is supported in a bearing 53 disposed at the upper end of a bracket arm 54 which 115 is bolted to the bearing 17, and the gear wheel 50 is driven by means of a spur gear wheel 55 keyed to the main power shaft 14. The flier member 10, which also supports the spool 9, is secured to one side of the 120 plate 6 by means of screws 57, and diametrically opposite to the flier member is a counterweight or balancing segment 58 similarly attached to the plate 6 by means of screws 59. The metal spool 9 is rotatably mounted 125 on a pin 60 that is secured to the flier member 10, and a screw 61 maintains the spool 9 in position on the pin 60 against the action of a compression spring 62.

The flier member 10 is flattened, at its 130

outer end, as shown at 63, and to this flattened end portion is removably attached, by means of a screw 64, a jewel-carrying plate 65 which contains a drilled diamond or other 5 jewel through which the filament wire is guided to the mandrel wire. I provide several jewel-carrying plates, the jewels in which are properly drilled to receive standard sizes of filament wire. The use of drilled 10 jewels is dispensed with in the winding of very small filament wire, since it is a tedious operation to insert the end of a very fine filament wire in a small opening. In winding wire of very large diameter the use of 15 jewels is likewise omitted, as a larger wire may be passed through the plain openings in the plate 65 than could be passed through a jewel supported in the manner described above. In these cases, the filament 20 wire is guided through plain openings in the plate 65.

In order to heat the filament wire while it is being wound upon the mandrel wire, electric current is supplied to the circular 25 plate 6, the periphery of which is made smooth to act as a slip ring and is engaged by a brush 70, shown in Figs. 3 and 5, which is held in a brush holder 71 supported on the bracket arm 54 and is pressed toward 30 the periphery of the disk 6 by means of a spring 72 which is compressed by means of a screw 72^a. Current is supplied to the brush 70 through a conductor 73, Fig. 2, and is controlled by a switch 74 and a rheostat 75. The conductor 73 is energized from any convenient source, which may be the low-tension side of a transformer 76 that receives current from a lighting circuit or any other suitable source of power. Current 35 entering the disk 6 from the brush 70 is prevented from passing to the gear wheel 50 by the insulating disk 52 but passes readily to the metal spool 9 and to the filament wire wound thereon and thence to the mandrel wire through the portion of the filament wire that is being wound. The circuit is completed from the mandrel wire through the frame of the machine and a conductor 78, which may conveniently be attached to 40 a bolt 77. On account of the small diameter of the portion of the wire 8 which carries the current from the spool 9 to the mandrel wire 1, this portion of the wire 8 is highly heated at the instant of winding, the exact 45 degree of such heat being controlled by means of the rheostat 75. I have found that a cherry-red heat is the most suitable temperature at which to wind ordinary tungsten wire.

50 In a modification of the apparatus for heating the wire which is shown in Fig. 4, I substitute, for the metal spool 9, an ordinary wooden spool, in which case, a metallic body, such as a pin or idler wheel 75^a, is secured 55 to the disk 6, and the filament wire is passed

around this metallic body after leaving the spool and before passing through the perforated guide plate 65. Electric energy is thus supplied to the wire through the plate and the metallic body 75^a. 70

Wire working machines have heretofore been provided with means for electrically heating the wire while it is being manipulated, but, in such prior devices, electric current has been supplied to the wire by means 75 of a brush resting upon the traveling wire itself. In practice, it is virtually impossible to maintain the brush in continuous even contact with the wire, and the sparking which ensues causes the wire to become pitted and therefore lessened in strength and impaired in radiating efficiency. The wire has also been sometimes heated by passing it through a mercury electrode, but harmful 80 sparking and pitting also occur in this 85 process.

By my heating device, in which the brush rests upon a smooth surface similar to the slip rings of rotary electric machines, such damage to the wire is avoided, and, at the 90 same time, the wire is highly heated only during its passage from the spool to the mandrel wire.

The winding drum 7, which receives the mandrel wire after the filament wire has 95 been wound upon it, is supported upon a vertical shaft 80 that is slidably mounted in a bearing 81 secured in a supporting bracket 82 which is bolted to the bed plate 24. The shaft 80 extends through another 100 bearing 83 in the bed plate 24 and is further extended beneath the base plate 24 for a purpose to be hereinafter described. Interposed between the shaft 80 and the bearing 83, as best shown in Fig. 6, is a sleeve 84, of 105 the form shown in this figure, which forms a bearing for the slidable shaft 80 and carries, secured to its upper end, a bevel gear wheel 85. Resting upon the bevel gear wheel 85 is a ratchet wheel 86 that is intimately secured to a sleeve 87, which surrounds the shaft 80 and is provided with keys 88 and 89 that are received in long longitudinal keyways 90 and 91 in the shaft 80. Secured to the bevel gear wheel 110 85, between the ratchet wheel 86 and the teeth of the bevel gear wheel, are a series of pawls 92 that engage the teeth of the ratchet wheel 86. It will be evident that, when the bevel gear wheel 85 is caused to rotate in 115 the proper direction, the pawls 92 and the ratchet 86 will cause the shaft 80 to rotate at the same angular speed, but that the shaft 80 is permitted to move longitudinally with respect to the ratchet mechanism by 120 reason of the engagement of the keys 88 and 89 in the keyways 90 and 91.

Superposed upon the ratchet wheel 86, and loosely surrounding the sleeve 87, is a plate 93, hereinafter called a pawl plate, 130

which carries, on its lower side, a second series of pawls 94 that engage the teeth of the ratchet wheel 86 and are adapted to rotate the ratchet wheel, and, consequently, 5 the shaft 80, in the same direction as the movement imparted to these parts by the pawls 92. The upper end of the sleeve 87 is provided with screw threads which are engaged by a nut 95, provided with a set 10 screw 96, by means of which the pawl plate 93 may be made to fit closely but movably upon the ratchet wheel 86. In order to insure that the ratchet mechanism just described shall be held rigidly in place, a 15 sleeve 97 is disposed between the upper end of the sleeve 87 and the bearing 81. The bevel gear wheel 85 is rotated continuously during the operation of the machine, and the pawl plate 93 is oscillated so as to impart 20 a periodical acceleration to the ratchet wheel 86. The gearing for effecting these independent movements of the bevel gear wheel 85 and the pawl plate 93 will now be described.

25 Power for continuously rotating the bevel gear wheel 85 is taken from the main power shaft 14, by means of a worm 100 meshing with a worm wheel 101 which is secured to a short shaft 102 that carries, at its outer 30 end, a spur gear wheel 103 meshing with an intermediate spur gear wheel 104 that is mounted on a pin 105 carried by an angularly adjustable slotted bracket 106. The spur gear wheel 104 may be of any desired 35 diameter, according to the speed at which it is desired to continuously rotate the drum 7, and it meshes with a spur gear wheel 107, secured to the outer end of a shaft 108, to the inner end of which is secured a bevel 40 pinion 109 meshing with the bevel gear wheel 85. If fine wire is to be wound, it may be preferable to substitute a worm wheel for the bevel gear wheel 85, in which case, the bevel pinion 109 is replaced by a 45 worm pinion. It will be evident from an inspection of the drawings that the train of gearing just described serves to rotate the bevel gear wheel 85 and the drum 7 continuously at a slow speed.

50 The pawl plate 93 is provided with an outwardly extending horizontal arm 110 that is integral with the plate 93 and is supported in a horizontal slot 111 in a guide support 112, as best shown in Fig. 1. The 55 outer end of the lever 110 is engaged by a series of internal cam faces or teeth formed in a circular cam disk 113 that is bolted to a circular plate 114 secured to the inner end of a short horizontal shaft 115 which is rotatably mounted in a bearing 116 formed in a standard 117 bolted to the bed plate 24. The lever 110 is pressed toward the cam disk 113, by means of a helical spring 118 60 enclosed within an opening in the head of the standard 112 and maintained in compression

within the said opening by means of a screw 118. The outer end of the lever 110 is provided with a roller 119 which rests against the cam surface of the disk 113.

The cam disk 113 is of the form shown 70 in Figs. 5 and 7, being provided with a number of notches 120 corresponding to the number of sections that are to compose each finished filament. A deeper notch 121 is provided for the purpose of causing the 75 formation of the coarsely wound terminal sections referred to above. In the operation of the machine, the disk 113 is caused to rotate in a clockwise direction, as seen in Figs. 5 and 7, and the lever 110 being yieldingly spring-pressed to the right, as described above, is engaged by one of the inclined cam faces of the disk 113 and is thereby forced to the rear, as seen in Fig. 1, thus rotating the pawl plate 93 in a counter-clockwise direction and causing the pawls 94 to drag idly upon the teeth of the ratchet wheel 86. When the rotation of the cam disk 113 brings the end of the lever 110 to one of the notches 120, it is forced quickly 80 into such notch by the action of the spring contained within the standard 112. This momentary rapid movement of the lever 110 causes the pawl plate 93 to rotate in a clockwise direction, and, through the pawls 94, imparts a momentary acceleration to the ratchet 86, which acceleration is transmitted to the drum 7 and causes the mandrel wire to be drawn past the winding device at a momentarily increased speed, thus 85 forming a loosely wound space or "break" in the helical filament. When the end of the lever 110 reaches the deep notch 121 in the cam disk 113, it will enter this notch, under the influence of the spring, and, on 90 account of the greater depth of this notch and the less abrupt angle at which it is formed, the pawl plate 93 will be caused to rotate at an accelerated speed which is somewhat slower than that caused by the 95 notches 120, but which continues for a longer period. The ratchet wheel 86 and the drum 7 will be accelerated during a corresponding period, and a coarsely wound terminal section of the filament will thereby 100 be formed.

Power for rotating the shaft 115, which carries the plate 114 and the cam disk 113, is derived from the main power shaft 14 by means of a worm 125 meshing with a 120 worm wheel 126 that is secured to a horizontal shaft 127, to which is also secured a miter gear wheel 128 meshing with a miter gear wheel 129 that is secured to a longitudinally extending short shaft 130 125 carrying, at its outer end, a pinion 131 meshing with an intermediate spur gear wheel 132 which is mounted on a pin 133 that is adjustably secured in an angularly adjustable slotted bracket 134. The spur 130

5 gear wheel 132 is of variable size, according to the speed at which it is desired to rotate the cam disk 113, and meshes with a gear wheel 135 that is secured to the end of the shaft 115 which carries the cam disk 113.

As stated above, the shaft 80 is extended below the bed plate 24. It terminates in a cam guide member 140 provided with an anti-friction roller 140^a that rests upon a heart-shaped cam 141 which is secured to a pin 142 rotatably mounted in a bearing 143 formed in the lower end of a depending bracket 144 secured to the under side of the bed plate 24 by means of bolts 145. The purpose of the heart-shaped cam 141 is to impart a vertical movement to the shaft 80, and, consequently, to the drum 7, during the operation of the machine, whereby the successive turns of wire carried upon the drum 7 are caused to lie side by side. For this purpose, the heart-shaped cam is caused to complete a half revolution while the machine is in operation a sufficient time to deposit enough turns of completed filament upon the drum 7 to substantially cover it. In order to impart slow rotation to the cam 141, power is derived from the bevel gear wheel 85 through a worm 147 which is keyed to the sleeve 84. The worm 147 meshes with a worm wheel 148 that is secured to a short horizontal shaft 149, which is rotatably mounted in a bearing 150 formed in an extension of the depending bracket 144 and carries, at its outer end a spur gear wheel 151. The gear wheel 151 meshes with an intermediate spur gear wheel 152 that is secured to a short shaft 153 adjustably secured in an angularly adjustable slotted bracket 154. The gear wheel 152, which is of a size corresponding to the speed at which the heart-shaped cam 141 is to be rotated, meshes with a spur gear wheel 155 that is secured to the short shaft 142 which also carries the cam 141. In order to maintain the cam guide 140 firmly upon the cam 141, I provide a bar 156 that extends transversely through the cam guide 140 and supports, at its outer ends, helical springs 157, shown in Fig. 2. The lower ends of the springs 157 are secured to any convenient stationary support, and their effect is to assist the force of gravity in maintaining the shaft 80 and the drum 7 yieldingly in their lowermost positions.

55 A roller 158 is adapted to rest against the face of the drum 7 to assist in maintaining the filament in place thereon as it is being wound. The roller 158 is rotatably mounted upon a pin 158^a that is secured to the outer end of an arm 159, the other end of which is rotatably secured to the upper end of a bracket arm 160 formed upon the bracket 82. A helical spring 161 surrounds the bracket arm 160, near its upper end, and serves to press the arm 159 in the proper

direction to effect close contact between the roller 158 and the wire wound upon the drum 7. The roller 158 is of special utility when fine coils are being wound. It prevents the filament-carrying mandrel from 70 unwinding from the drum in case of a break in the mandrel wire.

The manner in which the machine operates will be clear from the foregoing description, taken in connection with the drawing, and it will also be understood that the machine, when started, will automatically and continuously form sectional helical filaments. The total length that can be wound is limited only by the capacity of the wire-carrying spools 2 and 9. It is to be particularly observed that the machine is adapted to manufacture filaments of widely varying sizes and characteristics. The pitch of the filament helix is varied by increasing 80 or decreasing the speed of the winding drum, which is accomplished by varying the size of the gear wheels 101, 104 and 107. The diameter of the filament helix is varied according to the diameter of the mandrel 85 wire selected. The total number of turns in each filament is varied by increasing or decreasing the speed of the toothed cam disk 113, which is accomplished by changing the diameter of the gear wheel 132 mounted in 90 the angularly adjustable slotted bracket 134.

Ordinarily, one complete revolution of the cam disk 113 corresponds to one complete filament, but, if short filaments are desired, two or more of them may be made during 100 each revolution of the cam disk 113, two or more of the deep notches 121 being provided in such case. The number of sections in each filament is varied by altering the number of notches in the cam disk 113. 105 Each notch causes the formation of one of the spacing sections or "breaks," and, since these notches are distributed symmetrically around the cam disk, a cam disk having a given number of notches will form that 110 number of sections in each filament, no matter how many or how few may be the number of total turns in that filament. As stated above, the terminal sections are formed by the deeper notches in the cam 115 disk 113.

A feature which adds to the efficiency of the machine is the arrangement of the pawls 92 upon the bevel gear wheel 85. There are six of these pawls 92, and they are spaced 120 apart in a slightly unsymmetrical manner, the space between each pair of adjacent pawls differing from one sixth of the circumference of the ratchet wheel 86 by one sixth of the pitch of the ratchet wheel teeth. 125 On account of this arrangement, it is impossible for the ratchet wheel 86 to rotate in the direction opposite to its normal direction of rotation for more than one-sixth of the tooth pitch of the ratchet wheel 130

without striking one of the pawls 92 which thereupon acts as a holding pawl. Backlash between the ratchet wheel and the pawls is thereby reduced.

- 5 When a sufficient amount of filament has been wound, it is removed from the drum 7 and cut into single-filament lengths, the mandrel wire being thereafter dissolved out by means of a suitable acid.
- 10 A typical filament produced by my machine is illustrated in Fig. 8, which shows four main closely-wound filament sections 200, separated by spaces 201 and provided with coarsely-wound terminal sections 202.
- 15 If it is desired to vary the pitches of the turns that compose the main filament sections, this may readily be accomplished by modifying the shape of the cam teeth upon the cam disk 113. Such variation in the 20 pitches of the turns may be found desirable when the filament sections are to be mounted in a vertical position, in which case there may be danger of short circuiting between adjacent turns on account of the sagging of 25 the coils. It may therefore be advantageous to slightly spread apart the turns that are to constitute the lower part of such a vertical section in the manner illustrated in Fig. 9, wherein the lower turns 203 are of 30 greater pitch than the upper turns 204.

The machine described above is capable of numerous modifications which may be readily devised by skilled artisans without departing from the spirit and scope of my 35 invention. It is therefore to be understood that my invention comprehends all such modifications and changes as fall within the scope of the appended claims.

I claim as my invention:

- 40 1. A wire working machine comprising means for forming a filament into a non-overlapping helix upon a non-rotating mandrel at a predetermined pitch, and means for altering the said pitch at predetermined 45 intervals.

2. A wire working machine comprising means for forming a filament into a non-overlapping helix upon a non-rotating mandrel at a predetermined pitch, and automatically-actuated means for altering the 50 said pitch at predetermined intervals.

3. A wire working machine comprising means for forming a filament into a non-overlapping helix upon a non-rotating mandrel at a predetermined pitch, and means for altering said pitch at a plurality of different predetermined intervals.

4. A wire working machine comprising means for forming a filament into a non-overlapping helix upon a non-rotating mandrel at a predetermined pitch, and automatically-actuated means for altering said pitch at a plurality of different predetermined intervals.

- 65 5. A machine for forming wire helices

comprising means for moving a source of wire bodily around a mandrel, means for moving the said mandrel longitudinally at a predetermined rate and means for altering the said rate at predetermined intervals. 70

6. A machine for forming wire helices comprising means for moving a source of wire bodily around a mandrel and automatically-actuated means for moving the 75 said mandrel longitudinally at a predetermined rate and for altering the said rate at predetermined intervals.

7. A machine for forming wire helices comprising means for moving a spool of 80 wire bodily around a mandrel, means for moving the said mandrel longitudinally at a predetermined rate and means for altering the said rate at a plurality of different predetermined intervals. 85

8. A machine for forming wire helices comprising means for moving a spool of wire bodily around a mandrel, means for moving the said mandrel longitudinally at a predetermined rate and automatically-actuated means for altering the said rate 90 at a plurality of different predetermined intervals.

9. A filament-winding machine comprising means for drawing a filament wire from 95 a coil and wrapping it upon a non-rotating mandrel and means for connecting the said coil and the said mandrel to a source of electric current, whereby the said current is caused to traverse and heat the portion 100 of the filament wire between the said coil and the said mandrel.

10. A filament-winding machine comprising means for moving a coil of filament wire bodily around a mandrel and thereby 105 winding the said wire around the said mandrel and means for connecting the said coil and the said mandrel to a source of electric current, whereby the said current is caused to traverse and heat the portion of 110 the filament wire between the said coil and the said mandrel.

11. A filament-winding machine comprising means for moving a coil of filament wire bodily around a mandrel and thereby 115 winding the said wire around the said mandrel, means for longitudinally moving the said mandrel and means for electrically heating the said filament wire while it is being wound around the said mandrel. 120

12. A filament-winding machine comprising means for moving a coil of filament wire bodily around a mandrel wire, means for moving the said mandrel wire longitudinally and means for connecting the said 125 coil and the said mandrel wire to a source of electric current, whereby the said current is caused to traverse and heat the portion of the filament wire between the said coil and the said mandrel wire. 130

13. A filament-winding machine comprising a spool of electrically conducting material adapted to receive a coil of filament wire, means for drawing the said wire from the said spool and wrapping it around a non-rotating and longitudinally advancing mandrel and means for connecting the said spool and the said mandrel to a source of electric current, whereby the said current is caused to traverse and heat the part of the said filament wire between the said spool and the said mandrel.
14. A filament-winding machine comprising a spool of electrically conducting material adapted to receive a coil of filament wire, means for moving the said spool bodily around a mandrel and thereby winding the said filament wire around the said mandrel, means for longitudinally advancing the said mandrel and means for connecting the said spool and the said mandrel to a source of electric current, whereby the said current is caused to traverse and heat the part of the said filament wire between the said spool and the said mandrel.
15. A filament-winding machine comprising a spool of electrically conducting material adapted to receive a coil of filament wire, means for revolving the said spool bodily around a mandrel wire, means for longitudinally moving the said mandrel wire and means for connecting the said spool and the said mandrel to a source of electric current, whereby the said current is caused to traverse and heat the part of the said filament wire between the said spool and the said mandrel.
16. A filament-winding machine comprising a spool of electrically conducting material adapted to receive a coil of filament wire, a conducting support for the said spool, means for drawing the said filament wire from the said spool and wrapping it around a mandrel and means for connecting the said spool support and the said mandrel to a source of electric current, whereby the said current is caused to traverse and heat the part of the said filament wire between the said spool and the said mandrel.
17. A filament-winding machine comprising a spool of electrically conducting material adapted to receive a coil of filament wire, a rotatable conducting support for the said spool, the said support being electrically connected to the said spool but insulated from the remainder of the machine, means for rotating the said spool support to carry the said spool bodily around a mandrel and to thereby wind the said filament wire around the said mandrel and a brush engaging the said spool support and connected to a source of electric current that is also connected to the said mandrel, whereby the said current is caused to traverse and heat the part of the said filament wire between the said spool and the said mandrel.
18. A filament-winding machine comprising a spool of electrically conducting material adapted to receive a coil of filament wire, a rotatable conducting disk for supporting the said spool, a supporting plate of insulating material for the said conducting disk, a brush adapted to engage the periphery of the said rotatable conducting disk, means for rotating the said disk to carry the said spool bodily around a mandrel and thereby winding the said filament wire around the said mandrel and means for connecting the said brush and the said mandrel to a source of electric current, whereby the said current is caused to traverse and heat the part of the said filament wire between the said spool and the said mandrel.
19. A device for wrapping filamentary material around a mandrel comprising a revoluble plate provided with an axial aperture for receiving a mandrel, an insulating support for the said plate and a filament-carrying metallic spool secured to the said plate and adapted to be carried around the said mandrel when the said plate revolves.
20. A device for wrapping filamentary conducting material around a mandrel comprising a revoluble plate provided with an axial aperture for receiving a mandrel, an insulating support for the said plate, a filament-carrying metallic spool secured to the said plate and adapted to be carried around the said mandrel when the said plate revolves and a brush engaging the said revoluble plate for supplying electric current thereto.
21. A device for wrapping filamentary conducting material around a mandrel comprising a revoluble plate provided with an axial aperture for receiving a mandrel, an insulating support for the said plate, a filament-carrying metallic spool secured to the said plate and adapted to be carried around the said mandrel when the said plate revolves and a brush engaging the periphery of the said revoluble plate for supplying electric current thereto.
22. A device for wrapping filamentary material around a mandrel comprising a revoluble plate provided with an axial aperture for receiving a mandrel, a metallic filament-carrying spool secured to the said plate and adapted to be carried around the said mandrel when the said plate revolves, a balancing weight secured to the said revoluble plate diametrically opposite the said spool, and a revoluble member supporting the said plate and electrically insulated therefrom.
23. A device for wrapping filamentary material around a mandrel comprising a

revolute plate provided with an axial aperture for receiving a mandrel, a filament-carrying metallic spool secured to the said plate and adapted to be carried around the said mandrel when the said plate revolves, a member for guiding the said filamentary material from the said spool to the said mandrel, and a revolute member supporting the said plate and electrically insulated therefrom.

24. A device for wrapping filamentary material around a mandrel comprising a revolute plate provided with an axial aperture for receiving a mandrel, a revolute member supporting the said plate and electrically insulated therefrom, a filament-carrying metallic spool secured to the said plate and adapted to be carried around the said mandrel when the said plate revolves and a member for guiding the said filamentary material from the said spool to the said mandrel, the said guiding member comprising an arm secured to the said revolute plate with its outer end adjacent to the axis of the said plate and carrying at the said outer end, an apertured guide plate.

25. A device for wrapping filamentary material around a mandrel comprising a revolute plate provided with an axial aperture for receiving a mandrel, a filament-carrying metallic spool secured to the said plate and adapted to be carried around the said mandrel when the said plate revolves and a member for guiding the said filamentary material from the said spool to the said mandrel, the said guiding member comprising an arm secured to the said revolute plate, with its outer end adjacent to the axis of the said plate and carrying at the said outer end a removable member provided with a drilled jewel for receiving the said filamentary material and guiding it to the said mandrel.

26. A filament-winding machine comprising means for winding a filament wire upon a non-rotating mandrel wire and means for drawing the said mandrel wire past the said filament-applying means at a predetermined and variable rate.

50 27. A filament-winding machine comprising means for winding a filament wire upon a non-rotating mandrel wire, means for drawing the said mandrel wire past the said filament-applying means at a predetermined rate and means for varying the said rate at predetermined intervals.

55 28. A filament-winding machine comprising means for winding a filament wire upon a non-rotating mandrel wire, means for drawing the said mandrel wire past the said filament-applying means at a predetermined rate and automatically-actuated means for varying the said rate at predetermined intervals.

60 29. A filament-winding machine comprising

ing means for winding a filament wire upon a non-rotating mandrel wire, means for drawing the said mandrel wire past the said filament-applying means, at a predetermined rate and automatically actuated 70 means for varying the said rate at a plurality of different predetermined intervals.

30. A filament-winding machine comprising means for winding a filament wire upon a non-rotating mandrel wire, means for drawing the said mandrel wire past the said filament-applying means at a predetermined rate and means for varying the said rate at a plurality of different predetermined intervals.

80 31. A filament-winding machine comprising means for winding a filament wire upon a non-rotating mandrel wire, a drum for drawing the said mandrel wire past the said filament-applying means at a predetermined 85 rate and cam-controlled means for varying the said rate at predetermined intervals.

32. A filament-winding machine comprising means for winding a filament wire around a non-rotating mandrel wire and 90 means for drawing the said mandrel wire past the said filament-winding means, the said mandrel-drawing means comprising a drum and means for rotating the said drum at a variable speed.

33. A filament-winding machine comprising means for winding a filament wire around a non-rotating mandrel wire and means for drawing the said mandrel wire past the said filament-winding means, the 100 said mandrel-drawing means comprising a drum and a plurality of independently operated means for rotating the said drum at predetermined speeds.

34. A filament-winding machine comprising means for winding a filament wire around a mandrel wire, and means for drawing the said mandrel wire past the said filament-winding means, the said mandrel-drawing means comprising a drum and a 110 pawl-and-ratchet device for rotating the said drum at variable speed.

35. A filament-winding machine comprising means for winding a filament wire around a mandrel wire, and means for drawing the said mandrel wire past the said filament-winding means, the said mandrel-driving means comprising a drum, a ratchet adapted to rotate with the said drum and a plurality of independently-operated pawl 115 devices coöperating with the said ratchet to rotate the said drum at variable speed.

36. A filament-winding machine comprising means for winding a filament wire around a mandrel wire and means for drawing the said mandrel wire past the said filament-winding means, the said mandrel-drawing means comprising a drum, a ratchet adapted to rotate with the said drum, a plurality of independently-operated pawl 125 devices 130

- vices cooperating with the said ratchet to rotate the said drum in the same direction, means for moving one of the said pawl devices to operate the said ratchet continuously 5 and thereby to rotate the said drum at a predetermined rate and means for moving the other of said pawl devices intermittently and thereby to accelerate the rotation of the drum at predetermined intervals.
- 10 37. In a wire-working machine, a winding drum, a ratchet adapted to rotate the said drum, a set of pawls coaxially mounted with respect to the said ratchet and adapted to engage and rotate the said ratchet, means 15 for revolving the said set of pawls continuously at a predetermined speed, a second set of pawls also coaxially mounted with respect to the said ratchet and adapted to engage and rotate the said ratchet in the 20 same direction as the said first-named set of pawls, and a cam device for oscillating the said last-named set of pawls and thereby accelerating the movement of the said ratchet at predetermined intervals.
- 25 38. In a wire-working machine, a winding drum, a ratchet adapted to rotate the said drum, a set of pawls coaxially mounted with respect to the said ratchet and adapted to engage and rotate the said ratchet, means 30 for revolving the said set of pawls continuously at a predetermined speed, a second set of pawls also coaxially mounted with respect to the said ratchet and adapted to engage and rotate the said ratchet in the same 35 direction as the said first-named set of pawls, a support for the said last-named set of pawls and having an arm extending outwardly perpendicular to the axis of revolution of the said pawls and a rotatable cam 40 device mounted on an axis perpendicular to the axis of rotation of the said pawls and adapted to oscillate the said outwardly-extending arm and thereby to accelerate the movement of the said ratchet at predetermined 45 intervals.
39. In a wire-working machine, a driving ratchet, a set of pawls coaxially mounted with respect to the said ratchet and adapted to engage and rotate the said ratchet, gearing 50 for revolving the said set of pawls at a selectively predetermined speed, a second set of pawls, also coaxially mounted with respect to the said ratchet and adapted to engage and rotate the said ratchet in the same 55 direction as the said first-named set of pawls and a cam device for oscillating the said last-named set of pawls at selectively predetermined intervals.
40. In a wire-working machine, a driving 60 ratchet, a set of pawls coaxially mounted with respect to the said ratchet and adapted to engage and rotate the said ratchet, gearing for revolving the said set of pawls at a predetermined speed, a second set of pawls 65 also coaxially mounted with respect to the
- said ratchet and adapted to engage and rotate the said ratchet in the same direction as the said first-named set of pawls, means for yieldingly moving the said last-named set of pawls in their operative direction, a support for the said last-named set of pawls having an outwardly extending arm and a rotatable cam device provided with a plurality of notches adapted to successively engage and oscillate the said arm and to thereby accelerate the movement of the said ratchet at predetermined intervals. 70
41. In a wire working machine, means for winding a wire around a longitudinally movable mandrel, and means for advancing the said mandrel at variable speeds during predetermined time intervals, said last mentioned means comprising a driving ratchet and a set of pawls coaxially mounted with respect to the said ratchet and adapted to engage and rotate the same, the said pawls being unequally spaced around the said ratchet by a predetermined fraction of the tooth pitch of the said ratchet. 80
42. In a wire working machine, means for winding a wire around a longitudinally movable mandrel, and means for advancing the said mandrel at variable speeds during predetermined time intervals, said last mentioned means comprising a driving ratchet and a set of pawls coaxially mounted with respect to the said ratchet and adapted to engage and rotate the same, the said pawls being unequally spaced around the said ratchet by a fraction of the tooth pitch of the said ratchet obtained by dividing the said tooth pitch by the number of said pawls. 90
43. A filament-winding machine comprising a support of electrically conducting material, a spool secured to the said support for receiving a coil of filament wire, means for drawing the said wire from the said spool and for wrapping it around a mandrel, means for connecting the said support and the said mandrel to a source of electric current and means for electrically connecting the said wire to the said support after the said wire is drawn from the said spool and before it is wound on the said mandrel. 100
44. A filament-winding machine comprising means for continuously forming a filament wire into successive filaments, each of which consists of a plurality of main helical sections of a definite pitch separated by spacing sections of a greater pitch, the successive 110 filaments being set off by terminal sections composed of turns of greater pitch than the turns composing the said main sections. 115
- In testimony whereof I have hereunto subscribed my name this 21st day of December 1914. 120
